INVENTOR
ALLEN SMITH, JR.
BY
A.B. Bowman
ATTORNEY

UNITED STATES PATENT OFFICE.

ALLEN SMITH, JR., OF SAN DIEGO, CALIFORNIA.

INSECT-SWATTER.

1,342,974.

Specification of Letters Patent.

Patented June 8, 1920.

Application filed November 12, 1919. Serial No. 337,407.

To all whom it may concern:

Be it known that I, ALLEN SMITH, Jr., a citizen of the United States, residing at San Diego, in the county of San Diego and 5 State of California, have invented certain new and useful Improvements in Insect-Swatters, of which the following is a specification.

My invention relates to an insect swatter 10 and the objects of my invention are: first, to provide an elastic device for killing flies, mosquitos and the like; second, to provide a device of this class which will provide amusement and pastime as well as an effective insect killer; third, to provide a device of this class by the use of which insects on ceilings or other places where it is difficult to reach in other ways may be effectively killed and fourth, to provide 15 a device of this class which is very simple and economical of construction, durable, easy to operate, effective, and which will not readily deteriorate or get out of order.

With these and other objects in view as 20 will appear herinafter, my invention consists of certain novel features of construction, combination and arrangement of parts and portions as will be hereinafter described in detail and particularly set forth 25 in the appended claims, reference being had to the accompanying drawings and to the characters of reference thereon which form 30 a part of this application, in which:

Figure is a plan view of my insect swatter 35 assembled ready for use in the preferred form; Fig. 2 is an edge view thereof; Fig. 3 is a perspective view of the same in position ready for use; Fig. 4 is a fragmentary side elevational view of the handle and elastic connection in a slightly modified form 40 to that of Figs. 1, 2 and 3 and Fig. 5 is a similar view at a right angle thereto.

Similar characters of reference refer to 45 similar parts and portions throughout the several views of the drawings.

The handle member 1, elastic member 2, reinforcing fabric 3, reinforcing fabric 4, link 5, roller 6, clip 7 and swatting member 8 constitute the principal parts and 50 portions of my insect swatter.

In the preferred form of construction the handle member 1 consists of a flat metallic member folded intermediate its ends in curved form as shown best in Fig. 2 of 55 the drawings and the ends are corrugated at 1^a with conforming corrugations and

provided with a hole for a screw 1^b for securely clamping the end of the elastic member 2 between said members. It is preferred to provide the end of said elastic member with a hole through which the screw 1^b extends. This member 2 is provided with a reinforcing member 3, preferably fabric, to prevent wear and breakage of the member 2 where it is subjected to wear against the member 1. It will be noted that the extended ends of the member 1 are turned at 1^c providing a rounding surface for the engagement of the elastic member 2 and reinforcing member 3. 60 This elastic member 2 is of suitable length and its other end is provided with a loop by folding its end back against itself and mounted in this loop is a reinforcement 4 which is preferably fabric. Mounted inside 65 of this fabric is a link member 5 which is preferably a metallic link member provided with a roll 6 which is preferably a rubber roll. Mounted over the link 5 is a clip 7 which is a bifurcated clip between the two 70 members of which is secured the swatting member 8 which is shaped as shown best in Figs. 1 and 2 of the drawings, preferably composed of leather or similar material and the outer end is cut into a plurality 75 of strips forming lashes for swatting the insects.

The operation of the device is as follows: The handle member 1 is held in the one hand, the swatting member 8 in the other hand, the elastic member 2 stretched, aim taken and the swatting member released.

In the modified form of construction shown in Figs. 4 and 5 the handle member 95 is an ordinary handle shaped member 9 provided with a bifurcated clip member 10 in which is mounted a link 11 and the end of the elastic member 2 is folded back against itself with a reinforcement between 100 the folded portions and the link is provided with a rubber roller 11^a similar to the connection to the swatter in the preferred form.

Having thus described my invention what 105 I claim as new and desire to secure by Letters Patent, is:

1. An insect swatter, including a single non-branch handle member, a single longitudinally extendible elastic strip connected 110 to the one end of said handle member adapted to be turned to a position normally

at an approximate right angle thereto when in operative position, a swatting member pivotally connected to the opposite end of said longitudinally extendible elastic strip 5 with its free side provided with lashes adapted to contact with the insect.

2. An insect swatter, including a single longitudinally extendible elastic strip and

a relatively broad swatter member pivotally connected to one end thereof provided 10 with a plurality of lashes on its free side.

In testimony whereof, I have hereunto set my hand at San Diego, California, this 4th day of November, 1919.

ALLEN SMITH, JR.
